UNITED STATES PATENT OFFICE.

ARTHUR SCRIVENOR, OF RICHMOND, VIRGINIA.

GRINDING-MACHINE.

1,382,747.

Specification of Letters Patent. Patented June 28, 1921.

Application filed May 9, 1917. Serial No. 167,578.

To all whom it may concern:

Be it known that I, ARTHUR SCRIVENOR, a citizen of the United States, residing at Richmond, in the county of Henrico and State of Virginia, have invented certain new and useful Improvements in Grinding-Machines, of which the following is a specification, reference being had therein to the accompanying drawing.

10 My invention relates to machines for grinding cutting tools of cylindrical shape, and is described as used for grinding the threads or teeth of steel burs used in dressing grindstones, but it is not limited to such 15 use.

Objects of the invention are to provide means, for grinding spiral threads of several pitches at the same grinding or work speed, and without loss of time in the changing 20 of the machine from one pitch to another; for quickly setting the work so that the threads to be ground may be quickly brought into proper relation with the grinding means; for accurately indexing the 25 work; for rapidly bringing the work into and out of engagement with the grinding means during the process of grinding.

In the accompanying drawings, Figs. I, and II show the machine in plan and side 30 elevation respectively. Fig. III shows an example of cylindrical work having a spiral thread or cut. Fig. IV is a longitudinal section of the work spindle, mounted in its bearings. Fig. V is a diagram showing the 35 arrangement of the gearing driving the spindle shown in Fig. IV; and Fig. VI is an end view of the same arrangement. Fig. VII is a detail view of the grinding motor bracket, partly in section; Fig. VIII is a 40 detail, in plan, of the knee supporting the grinding motor bracket; and Fig. IX is a detail showing the grinding motor in operative position.

In Figs. I and II the numeral 1 designates the bed of the machine. In Fig. II the lower part of the bed is not shown. To the side of the bed is bolted a bracket 2 for the purpose of carrying a motor 3, or other driving mechanism. Driven by the motor is 45 a worm gearing contained in the housing 4. The worm is carried by the shaft 5, which may be directly connected, or by means of a flexible coupling, with the shaft of motor 3; and the worm wheel is carried by the sleeve 50 of a friction clutch 6, which sleeve is free to revolve on the shaft 7 carried in bearings

9, 10 and 11. The gripping element 12 of the clutch 6 is prevented from turning on the shaft 7 by means of a feather. When the clutch is open, though the motor is running, the shaft 7 will not revolve. When the clutch is closed, and the motor is running, the shaft 7 will revolve. This arrangement is not more fully illustrated as it is one in common use in power transmission. 60 For the same reason the full clutch rigging, such as levers, pivots, are not shown; the grooved portion 13 being sufficient to indicate the sliding part of the clutch. The ratio of the shaft and motor speeds is the 65 same as that of the worm gearing.

Upon the shaft 7 is mounted the gear 14, engaging with the gear 15 which is carried on a countershaft 16 mounted in bearings 17, 17. The gear 15 is preferably feathered 75 to the shaft, so that it may be slid out of engagement with the gear 7 after withdrawing the securing pin or set screw 18.

Also mounted on the shaft 16 is the gear 19, which engages with another gear 20, the 80 function of which will be explained later.

Slidably mounted on the shaft 7 is a sleeve 21, which may be secured in position by means of a locked screw 22, as shown in the detail drawing Fig. V. On the sleeve 85 21 are the gears 23, 24, 25, 26, and 27.

Below the shaft 7, and mounted in bearings 28 and 29—see Fig. II and detail Fig. V—is the shaft 30, on which are secured the gears 31, 32, 33, 34, 35, and 36. The gears 90 not shown in engagement are arranged to engage as follows: 23 with 31, 24 with 32, 27 with 35, and 26 with 34. Gear 25, which is also mounted on the sleeve, 21, may, as shown, engage with gear 33. Gear 36 engages at all times with the gear 40. In Fig. V the teeth of the gears are not shown. Instead, the gears are shown bounded by their pitch circles, so that the relation between one gear and another may be readily seen. 100

Motion being imparted to the shaft 7 in the direction shown by the arrow, fixed gear 14, and sliding gears 23, 24, 25, 26 and 27 will revolve in the same direction. Consequently 15 and 19—on the countershaft 16—105 will revolve in the opposite direction, and 20 in the same direction as shaft 7. Also, through the engagement of the change gears, 36 will run in an opposite direction to, and 40 in the same direction as the shaft 7, 110 and consequently in the same direction as gear 20. As the gears 23, 24, 25, 26 and 27

and their mates 31, 32, 33, 34, and 35 are of different diameters they will be revolved at a predetermined fixed speed, the gear 40 may be revolved at five different speeds, each one bearing a certain ratio to the speed of the gear 20. And no matter what the speed of the motor, of the shaft 7 and of gear 20, may be, the ratios between the speed of the gear 20 and the several speeds of gear 40 10 will not change.

Reference to Fig. IV will show that the two gears 20 and 40 operate and control the work spindle 50—shown in this Fig. IV in two parts on account of its length. It is 15 actually in one straight piece.

Gear 20 is mounted on a sleeve 41 which is carried by ball bearings 42 and 43, housed respectively in the bearing stands 44 and 45. Bearing 43 is of a thrust type to limit end- 20 wise motion of the sleeve 41, and so allow for a nice adjustment, with a minimum of opening and a minimum of friction, between the gear body and the adjacent bearing covers 46 and 47. In the spindle 50 is a 25 long slot or featherway 48, in which freely, but closely, engages the tongue 49, which is inserted through and secured in the hub of the gear 20. Consequently when the gear 20 revolves, the tongue 49 causes the spindle 30 50 to revolve in the same direction, and at the same speed. At the same time the endwise movement of the spindle is not controlled by the gear 20 nor tongue 49. The sleeve 41 is a close sliding fit on the spindle 50, and, being mounted in ball bearings, will practically prevent any side play in the 35 spindle. Furthermore should the bore of the sleeve wear larger, the sleeve can be readily replaced by a new one.

40 Though any kind of good bearing may be used for the spindle sleeves, I prefer ball bearings because they permit of more accurate adjustments with a minimum of friction and a minimum of attention. The annular grooves, such as 51, 51, shown in the body of gear 20, and in bearing closures 46, 47, etc., are to hold grease for the purpose of keeping grit or water out of the bearings. The bearings 42 and 43 are held 45 in their respective places on the sleeve 41 by the lock-nuts 52 and 53. Similar lock-nuts are shown securing other ball bearings. Attached to the bearing cover 46 and to the gear 20, and elsewhere, are shown felt or 50 leather washers 54 held in place by means of rings, 55, in turn held by screws or bolts. The object of these washers is to prevent as far as possible dust from entering between rotating and stationary parts.

60 Gear 40 is rigidly attached to the sleeves 57 and 58, which are bored a close running fit for the spindle 50. These two sleeves are carried in the bearings 59 and 60, housed respectively in the stands 45 and 61. 62 and 63 are bearing closures. Endwise mo-

tion of the gear 40 is prevented by the thrust bearings 64 and 65, acting against the thrust block 66, bolted to stand 61. The end of the spindle is protected by means of the cover 67. The openings 68 in the several stands and the end cover are for lubrication. 70

Set in the hub of gear 40, and secured by means of a screw 69, is the nut 70, engaging a thread cut on the spindle 50. For the present it will be sufficient to note that if rotation of the spindle is prevented, rotation of gear 40 will give the spindle endwise movement. Also, if at the same time the gear 20 transmits rotary motion to the spindle, the said spindle will then rotate and also have endwise movement; except when gears 20 and 40 have the same rotary speed. Hereinafter the connection between the gears shown in Fig. IV and the two motions of the spindle 50 will be further explained. 75 80 85

The work carrying end of the spindle 50 is shown in the upper part of Fig. IV. This part of the spindle 50 is a sliding fit in the sleeve 75, which is carried in bearings 76 and 77, held in place by lock-nuts 78, 79, 90 and mounted in the housing 73 which forms a part of the stand 44. The housing terminates with the closure 74.

Outside the closure 74 and rigidly secured to the spindle 50 is a head 80, to which is 95 screwed an annular piece 81 carrying a sleeve 82 of sufficient length to protect from dust the opening between the closure 74 and the head 80 throughout the movement of the spindle 50. The head 80 is secured against endwise movement by means of the collar 83.

84 and 85 are ring oilers. At 86 is shown an oiling device consisting of a bent pipe which, as the sleeve revolves, will pick up oil from the bottom of the housing 73, and allow it to drain through the sleeve 75 on to the spindle 50. The holes 87 will allow oil picked up by the ring 84 to pass through to the spindle. 105

The "work" to be ground is shown at 90, 110 and in this case consists of a hollow cylinder having chased on its outer surface a spiral thread, the edge or point of which it is my object to grind.

The work having an inner cylindrical surface is held on suitable cone shaped heads 91 and 92. The head 91 is attached to a sleeve 93 which is a close fit on the spindle 50. The head 92 is bored to slide closely on the other end of the sleeve 93. At 94 is a 115 lock-nut for drawing the head 92 up on the sleeve 93, and so locking the work 90 in position and concentric with the spindle 50. It will be noted that the sleeve 93, with the heads 91 and 92, the lock-nut 94, and the work 90 may be removed from the spindle 50 without disturbing their relative positions. This enables me to use a number of work heads and sleeves, all set up with work, ready for attachment to the spindle. 120 125 130

It also enables me to rotate the work around the spindle, for adjustment to the grinder, without endangering their concentricity.

The work heads are secured on the spindle 50, and against the head 81, by means of the nut 95 and washer 96. It will be seen that if nut 95 is slackened, the work head may be rotated; and that if nut 95 is removed, the work may also be removed.

10 Sliding on vertical guides at one end of the bed 1 is the knee 100 (see Figs. I and II), which is adjustable vertically by means of the screw 101 working in the fixed nut 102 and journaled in the bearing 103. The screw 15 101 has at its upper end the worm wheel 104 which is engaged by the worm 105 mounted on a shaft carried in bearings 106 and 107, and provided with the hand wheel 108 and dial 109.

20 On the knee 100 is carried the grinding wheel 110 mounted on a shaft which may be driven by pulleys and belts from overhead lines, or by means of an electric motor, as shown at 111 in Fig. I. The motor is omitted 25 in other figures to allow other details to be more clearly seen. The motor 111 is preferably mounted on a bracket 112 which is pivoted on the knee 100 at a point exactly beneath the center of the abrasive wheel 110.

30 In Fig. I the bracket 112 is shown pivoted at 113; but when the work shown at 90 is in process of grinding, the bracket 112 is pivoted immediately under the center line of the spindle 50, and a little in advance of the 35 end of the work 90, at a point 114 indicated by the head of the arrow in Fig. II. Also as shown in detail in Fig. IX. Thus, as the work 90 is advanced by the movement of the spindle 50 its center line intersects a vertical 40 line dropped from the center of the abrasive wheel 110.

As shown in Fig. VII the motor bracket 112 is provided with slots 115 and 116, through which, and the holes 117, 118, 119

45 and 120 in the knee 100, shown in Fig. VIII, tap bolts are used to clamp the motor bracket in the desired positions. The motor bracket clamped in position for operating on the work 90 is shown in Fig. IX. In this case 50 the pivot 114 is a fixed point, and the center line of the motor may be set at various angles with the center line of the work spindle 50 for the grinding of work having spiral threads of different pitches.

55 The work 90 carried by spindle 50 has a spiral thread, and the gearing shown in Fig. V provides for the grinding of threads cut 6, 7, 8, 9 and 10 to the inch.

Referring to Figs. I and V: The shaft 7 60 is driven by the motor 3, through the clutch 6 and worm gearing 4, at a given speed. The gear 14 has the same speed as the shaft 7. Gears 15 and 19 are of the same pitch diameter as gear 14, and consequently have 65 the same number of revolutions per minute

as the shaft 7. Gear 20, which rotates the spindle 50, may be of any suitable size, and is sufficiently large to provide the necessary clearance between bearing housings 45, 61, and other mechanisms. In the drawings the gear 20 is shown two and one third times greater in pitch diameter than gears 19, 15 and 14. Consequently the rotary speed of gear 20 will be three sevenths of the rotary speed of shaft 7. 75

Gear 40, which drives the nut 70, (see Fig. IV) is of the same pitch diameter as gear 20; and gear 40 is driven by gear 36 on the shaft 30. Gear 36 is equal in pitch diameter to gears 14, 15 and 19. If the two 80 shafts 7 and 30 were given the same speed, the two gears 20 and 40 would also have the same speed of rotation; therefore the spindle 50 and the nut 70 (in gear 40) would have the same rotary speed, and there would be 85 no endwise movement imparted to the spindle 50.

In order to grind a spiral thread on the work 90, endwise movement is necessary, and proportional to the pitches of the thread, 90 which we have taken as 6, 7, 8, 9, and 10 to the inch. To follow these pitches it is necessary to give to the gear 40 different rotary speeds having definite relations to the rotary speed of the gear 20. This I do through the gears 23, 24, 25, 26, 27, and gears 31, 32, 33, 34, and 35, which, as before stated, engage with one another as follows:—23 with 31, 24 with 32, 25 with 33, 26 with 34, and 27 with 35; the gears 23 to 27 being mounted on a sliding sleeve, feathered to the drive shaft 7, and which may be slid to the right or to the left to bring the several pairs of gears into engagement. 95

In order that these gears may occupy as 105 short a length as is practicable, the pair having the greatest ratio is placed between the other pairs, two being on either side of it; and the pairs having the two smallest ratios are placed one at each end of the line. (Note 110 that the gear 36 is not a change gear, but is a fixed gear driving gear 40, and located where shown to enable me to conveniently place gear 40. It is not a consideration in the explanation of the arrangement and 115 functions of the change gears, except as imparting motion from the shaft 30 to the gear 40.) This arrangement allows clearance between all gears except the engaging pair, as well as a saving of space and material. 120

To grind spiral threads the work must first be given a rotary motion to give a desirable grinding speed; that is the speed, in feed per minute, at which the thread is presented to the action of the abrasive. The 125 work must at the same time be advanced toward the abrasive at a definite speed corresponding with the pitch of the thread. It will be seen that to grind threads of 6, 7, 8, 9, or 10 to the inch, for every complete revolu- 130

tion of the work the said work must be advanced $1/6, 1/7, 1/8, 1/9$ or $1/10$ of an inch. The same of course applies to the work spindle 50, and to produce the stated advances per revolution in this spindle the gearing shown in Figs. I, II, IV and V is designed. Note also that no matter what the speed of the shaft 7, or of the motor 3, the required ratios between the speeds of the gears 20 and 40 will be preserved.

If the spindle 50 be rotated, the nut 70 meanwhile being stationary, or if the nut 70 be rotated and the spindle 50 being stationary, the lengthwise movement or advance of the spindle will equal the pitch of the screw thread, by the number of revolutions, the direction of advance depending upon the hand of the screw thread, or upon the direction of rotation of the spindle or the nut.

20 The burs to be ground are usually provided with a right hand thread, and when the work is to move from right to left—referring to Fig. I—the spindle is given a right hand rotation, and vice versa. Observed from the right end of the machine in Fig. I, a right handed motion is clockwise. Also if the screw thread on the spindle 50 be right handed, and both gears 20 and 40 be revolved clockwise, the spindle will move from left to right so long as the revolutions per minute of the gear 40 are less than those of gear 20, for clockwise rotation of gear 40 either alone, or with, but at a greater speed than gear 20, will cause the spindle to move 35 from left to right. We can also cause the spindle to move to the right by causing the gears 20 and 40 to rotate anti-clockwise. The advance of the spindle 50 per revolution depends upon the relation between the

40 rotative speeds of the gears 20 and 40, and from the above explanation it can be shown that the advance is equal to the pitch of the screw minus the said pitch multiplied by the ratio of the rotary speed of the gear 40

45 to that of the gear 20; and if A is the advance, P the screw pitch, and R_1 the gear ratio, then $A = P(1 - R_1)$. If R_2 is the ratio of the gear 20 to gear 19, and gears 15 and 14 are equal and also equal to gear 36 which

50 has a ratio to gear 40 R_3 ; then $A = P(1 - R_2 \times R_1 \times R_3)$ from which it is seen that if the gears 20 and 40 are alike in size, and gears 19, 15, 14, 36 are alike, that no matter what size we give to gears 20 and 40 and to

55 19, 15, 14, 36, the formula for the advance will always be $A = P(1 - R_1)$; and the pitch being constant the advance and the speed ratio of the gears 20 and 40 are the only variables. But if the gears 19, 15, 14, and

60 36 are alike in size, then the ratio of the speeds of shafts 7 and 30 must be the same as the desired speed ratios of the gears 20 and 40; so we find that for any advance of the spindle 50 the formula may be

65 $A = P(1 - R_4)$; in which R_4 represents the

ratio of any one of the pairs of gears on shafts 7 and 30; and this formula may also be written $R_4 = 1 - \frac{A}{P}$.

Burs may be cut to any number of threads per inch, within practicable limits; and my machine may be used to grind any number of threads per inch, it only being necessary to provide suitable change gears on the sleeve 21 and shaft 30, which may be made as long as necessary. In the drawings I have shown the gearing on sleeve 21 and shaft 30 as designed for grinding threads from 6 to 10 per inch. By extending the sleeve and shaft other gears could be added for other threads.

The advance per revolution of 6 threads per inch is $1/6''$; for 7 threads per inch, $1/7''$; for 8 threads, $1/8''$; and so on. By using the formula $R_4 = 1 - \frac{A}{P}$, I find that the

85 required gear ratios for the several threads are:—for 6 threads, $1/3$; for 7 threads, $3/7$; for 8 threads, $1/2$; for 9 threads, $5/9$; for 10 threads, $3/5$.

90 Manifestly if the pitch of the screw equals one of the desired rates of advance, either one of the gears 20 or 40 must not revolve. And if the pitch of the screw is intermediate the extreme rates of advance, then motion of the gearing in two directions for one direction of advance would be necessary. Therefore to make the arrangement as simple as possible I use a screw pitch which is less than any rate of advance for which the 95 machine is designed. This allows positive motion of all gearing, and also motion in only one direction of gearing for advance of the spindle in a given direction.

Having established the gear ratios, the 100 centers between the sleeve 21 and shaft 30 are chosen so that gears of the required sizes may be used. This distance must be such that each pair of gears will have the desired ratio, and also a whole number of 105 teeth. Adding together the numerator and denominator in the gear ratios found above we have, 4, 10, 3, 14, and 8. Each of these numerals is a standard pitch or a factor of a standard pitch; so for the distance between 110 centers we can use any whole number, or a factor of a whole number, for instance $1\frac{1}{2}$, 2, $2\frac{1}{2}$, 3 $3\frac{1}{2}$, 4, $4\frac{1}{2}$, 5, etc. But there are practical limits set by the diameter of the sleeve 21 and the available space in the machine; 115 and I have found centers of $3\frac{1}{2}$ ", using a suitable tooth pitch for each pair of gears, to be convenient.

In Fig. III is shown a bur having spiral 120 teeth or cuts. Burs are also made with straight, and with diagonal cuts; and combinations of spiral and straight, and of diagonal and straight cuts are also used to form interrupted teeth of various lengths and pitches. The diagonal and straight cut 125

burs I grind on another machine, described and claimed in another application filed November 13, 1917, Serial No. 202,621, and which machine for the sake of convenience I build as an attachment to the machine described in this specification, and as indicated in Figs. I and II of the drawings, wherein 90° is the work secured to a revolute spindle 150, mounted in bearings 151 secured to a table 164. The table may be reciprocated by means of the handle 170 so as to carry the work toward and from the abrasive wheel 110 (see Fig. I), the rotary motion of the work being controlled by the cam 152 attached to the spindle 150, and in its turn controlled by the cam finger or roller 161, and also by the indexing device 153. The table 164 slides in the vertical guide 173, which in turn is adjustable vertically on the knee 100 by means of the screw motion 174, 175, Fig. II. Vertical reciprocating motion is imparted to the work 90° during grinding through the handle 182, Fig. I.

If desired, an automatic stop and reversing motion may be applied to the spindle 50 and motor 3, and an automatic cut out for the clutch 6. The gears 14 and 19 may be so mounted on the shaft 16 that either may be loosened and slipped out of gear. When so disengaged, the spindle may be caused to move endwise, or may be rotated by hand, which features are of use in setting work.

I have described my machine as arranged for grinding bur and similar threads; but it can with advantage be used for grinding other articles in which precision is required, such as pistons, sleeves; the rate of feed being readily adjustable through the gear drives of the gear wheels 20 and 40.

In the claims I have referred to the rectilinear motion of the work spindle as the advance, for the sake of brevity; and it is to be understood that by "advance" I refer to motion in line with the axis in either direction, toward or from the grinding wheel.

I claim—

1. In combination, a sleeve rotatably mounted in bearings and having an internally threaded portion, a work holder mounted slidably in and concentrically with the sleeve and provided with an externally threaded portion adapted to engage the internal thread of the sleeve, means for rotating the sleeve, means for rotating the work holder, and differential means for changing the ratio between the rates of rotation of the sleeve and of the work holder.

2. The combination of a bed, bearings mounted on the bed, a sleeve rotatably mounted in the bearings, a spindle rotatably and slidably mounted in and concentrically with the sleeve, means for rotating the spindle, a screw thread on the spindle, a nut engag-

ed in its rotation to give to the spindle an endwise movement, and means for rotating the nut at a speed having a predetermined ratio to the speed of rotation of the spindle.

3. The combination of a bed, bearings mounted on the bed, a sleeve rotatably mounted in the bearings, a spindle rotatably and slidably mounted in and concentrically with the sleeve, means for rotating the spindle, a screw thread on the spindle, a nut engaging the thread on the spindle and adapted in its rotation to give to the spindle an endwise movement, means for rotating the nut, and differential means for changing the ratio between the rotation of the shaft and the rotation of the nut.

4. The combination of a bed, housings mounted on the bed, annular bearings mounted in the housings, sleeves rotatably mounted in the bearings, a work spindle mounted in the sleeve and having a threaded portion, means for rotating the spindle, a nut engaging the threaded part of the spindle, and means for rotating the nut.

5. The combination of a bed, housings mounted on the bed, annular bearings mounted in the housings, sleeves rotatably mounted in the bearings, a work spindle mounted in the sleeve and having a threaded portion, means for rotating the spindle, a nut engaging the threaded part of the spindle, means for rotating the nut, and differential means for changing the relation between the speeds of rotation of the spindle and the nut.

6. The combination of means for dressing a thread on cylindrical work, means for supporting the work, means for rotating the work, means for advancing the work, and a train of gearing for actuating the rotating means and the advancing means at such proportional speeds that the advance of the work to the dressing means will have the required relation to the pitch of the thread on the work.

7. The combination of means for dressing a thread on cylindrical work, means for supporting the work, means for rotating the work, means for advancing the work, and selectively arranged gearing for actuating the advancing means at predetermined speeds proportional to the rate of rotation.

8. The combination of a work spindle having a threaded part, means for securing cylindrical work on the spindle, means for dressing the surface of the work, means for rotating the spindle, a nut engaging the threaded part of the spindle, means for rotating the nut, and means controlling the relation between the rotation of the spindle and the rotation of the nut, so that the work shall advance toward the dressing means at the desired speed proportional to its speed of rotation.

9. The combination of a spindle mounted

90

95

100

105

110

115

120

125

130

in bearings and having a screw-threaded portion, a rotary nut engaging the thread on the spindle, and confined as to motion in a horizontal plane, means for rotating the 5 spindle, means for rotating the nut, and differential means for controlling the speed of rotation of the nut.

10. The combination of a spindle mounted in bearings and having a screw-threaded portion, a rotary nut engaging the spindle thread and adapted on being rotated with reference to the spindle to advance the spindle, means for rotating the spindle, means for rotating the nut, differential 15 means controlling the relation between the rotation of the spindle and of the nut, said differential being equal to unity minus the ratio of the desired spindle advance per revolution to the pitch of the spindle thread.

20. 11. A differential controlling the relation between the rotation and the rectilinear movement of a shaft, and consisting of means for rotating the shaft, rotary threaded means engaging the shaft to give endwise motion to the shaft, geared means for changing the speed of the rotary threaded means per revolution of the shaft, the ratio of said geared means being equal to unity minus the ratio between the desired 25 rectilinear motion of the shaft per revolution, and the pitch of the threaded means.

12. The combination of a spindle mounted in bearings, and having a screw-threaded portion, a rotary nut engaging the thread of the spindle, and confined as to motion in a horizontal plane, means for rotating the spindle in the nut, and differential means actuating the spindle rotating means and also rotating the nut and adapted to change 35 the ratio between the rotary and rectilinear motions of the spindle.

13. The combination of a spindle mounted in bearings and having a threaded portion, a nut engaging the thread of the spindle, means for rotating the spindle, means for rotating the nut, and differential means for changing the relative speeds of the shaft rotating means and the nut rotating means to change the ratio between the rotary and rectilinear motions of the shaft.

40. 14. The combination of a shaft mounted in bearings, means for rotating the shaft, means for imparting rectilinear motion to the shaft, a second shaft, a gear mounted on the second shaft and arranged to actuate the means for imparting rectilinear motion to the first shaft, a set of gears of different pitch diameters mounted on said second shaft, a third shaft parallel to the second shaft, a sleeve slidably mounted and feathered on the third shaft, a set of gears mounted

ed on the sleeve and each one being adapted to engage one of the gears on the second shaft, and so arranged that only one pair of gears will be in engagement at one time, 45 and means for rotating the third shaft.

15. The combination of a shaft mounted in bearings, means for rotating the shaft, means for imparting rectilinear motion to the shaft, a second shaft, a gear mounted on the second shaft and arranged to actuate the means for imparting rectilinear motion to the first shaft, a set of gears of different pitch diameters mounted on said second shaft, a third shaft parallel to the second shaft, a sleeve slidably mounted and feathered on the third shaft, a set of gears mounted on the sleeve and each one being adapted to engage one of the gears on the second shaft, and so arranged that only one pair of gears will be in engagement at one time, 50 each pair of gears being so proportional that the rectilinear motion of the first shaft shall be 1/6", 1/7", 1/8", 1/9", and 1/10", respectively, per revolution of the first shaft, and means for rotating the third shaft.

16. The combination of a shaft mounted in bearings, means for rotating the shaft, means for imparting rectilinear motion to the shaft, a second shaft, a gear mounted on the second shaft and arranged to actuate the means for imparting rectilinear motion to the first shaft, a set of gears of different pitch diameters mounted on said second shaft, the largest gear being placed in the middle of the row of gears, and the remaining gears being located on either side of the largest gear and in descending sizes, a third shaft parallel to the second shaft, a sleeve 55 slidably mounted and feathered on the third shaft, a set of gears mounted on the sleeve and each one being adapted to engage one of the gears on the second shaft, and so arranged that only one pair of gears will be in engagement at one time and means for rotating the third shaft.

17. The combination of a spindle mounted in fixed bearings and adapted to rotate and to move in the direction of its axis, 60 means for securing the work on the spindle, means for rotating the spindle, and rotatable means for advancing the spindle at a speed having a predetermined relation to the speed of rotation of the spindle.

In testimony whereof I have hereunto affixed my signature in the presence of two witnesses:

ARTHUR SCRIVENOR.
